UNITED STATES PATENT OFFICE.

THOMAS STENHOUSE, OF WASHINGTON, PENNSYLVANIA, ASSIGNOR TO HAZEL-ATLAS
GLASS CO., OF WHEELING, WEST VIRGINIA, A CORPORATION OF WEST VIRGINIA.

FORMING MACHINE.

Application filed November 23, 1923. Serial No. 676,570.

The invention relates to machines for the manufacture of jugs, jars and similar articles, and particularly to a machine in which the glass charges are fed to blank molds of greater cross-sectional area than that of the neck mold, and in which the automatic positioning of the neck mold having restricted area is subsequent to the delivery of the charge to the blank mold, and prior to the pressing operation whereby the article is partly formed.

The invention involves various novel features, advantages in construction, and methods of operation, and all such improvements will be apparent to those skilled in the art from the following detailed description when taken in connection with the accompany drawings, in which:

Figure 1 is a plan view of the complete apparatus.

Figure 2 is a more or less diagrammatic view to show the position of the various molds at different stations, and to show the two cam tracks and the operating connections between the cams and the molds.

Figure 3 is a vertical sectional view of the apparatus; the section being taken through the diametrically opposed stations B and G; that is, through the pressing station and the delivery station. The lower portion of the apparatus is shown in elevation.

Figure 4 is a vertical sectional view through station B, or the pressing station, but on a larger scale than Figure 3.

Figure 5 is a vertical sectional view through station C, or the cooling station.

Figure 6 is a vertical sectional view through station D, or the first blowing station.

Figure 7 is a vertical sectional view through station E, or the second blowing station.

Figure 8 is a detail view of the blank mold charged with glass, as at station A, or the charging station.

Figure 9 is a detail view of the blank mold at station B, or the pressing station; the plunger having been inserted and the glass forced into the neck and handle.

Figure 10 is a detail view of the molds at station C, or the cooling station; the blank mold having been withdrawn, leaving

the glass blank suspended from the neck mold, and the air cooling means inserted in the interior of the blank.

55

Figure 11 is a detail view of the molds at station D, or the first blowing station, and showing the first blowhead positioned on the neck mold.

Figure 12 is a detail view of the molds at station E, or the second blowing station, and showing the neck mold open and the second blowhead positioned on the body mold.

Figure 13 is a detail view of the molds at station F; both molds being open and the article resting on the mold bottom.

Figure 14 is a detail view of the molds at station G, or the delivery station; both molds being open, and the mold bottom having been withdrawn, carrying the article with it ready to be picked up and delivered to a conveyer by the transfer device.

Figure 15 is a detail view, showing the means by which the blank mold is mounted for vertical reciprocatory movement.

Figure 16 is a detail view of the cams and associated parts, and showing the means for maintaining the cam-operated slides in radial vertical alignment and for causing the upper and lower slide plates to rotate together and with the mold table.

Figure 17 is a vertical sectional view of the first blowhead and the mechanism by which it is operated.

85

Figure 18 is a sectional detail view of the second blowhead disconnected from its operating mechanism.

Figure 19 is a plan view of one of the clamps for securing the molds in closed position.

Figure 20 is a vertical sectional view of the automatic transfer device, and

Figure 21 is a developed view of the track for elevating the blank mold.

95

Referring to the drawings more in detail, numeral 1 indicates the usual column on which is rotatably mounted the ordinary table 2 carrying a series of molds; ten molds being illustrated in the present instance; though, of course, the number may be varied as desired.

100

The column 1 is hollow, as shown in Figure 3, and an air supply pipe may be connected

to the flange 3, or the air may be introduced through the bottom of the column; the purpose being to maintain a reservoir of air in the column for cooling the molds. The column has ports 4 therein for the purpose of providing communication between the interior of the column and the interior of the casting 5, as shown in Figure 7.

The air may be supplied from the casting 10 5 to the blank molds in any desired manner. The construction shown herein consists of a conduit 180 having a nozzle 181 provided with suitable apertures, and being curved to deflect the cooling air against the molds. 15 An ordinary sliding damper 182 is mounted in the conduit for controlling the volume of air supplied, and for shutting the supply off entirely when desired.

The means for mounting the mold-carrying 20 table and for rotating it step by step will first be described.

The casting 5 is recessed to receive a ball-bearing race 6, and the lower side of the mold-carrying table 2 is recessed to receive 25 a cooperating race 7, thus providing a ball-bearing mounting for the table.

The table is given an intermittent rotary movement by means of a Geneva stop construction, and for this purpose the table is 30 provided with a series of alternate slots and curved recesses, as indicated by numerals 8 and 9, respectively (Figure 1). A Geneva wheel 10 carries a roller 11, and when this roller enters the slots 8 the table is driven, 35 and when the roller passes out of one of the slots the adjacent curved recess 9 is engaged by the peripheral portion 12 of the Geneva wheel, thereby locking the table against rotation. Referring particularly to Figure 6, the 40 Geneva wheel is fixed to a vertical shaft 13 which is mounted in bearings 14, 15 and 16. Loosely mounted on the shaft 13 is a worm wheel 17; the worm wheel being caused to rotate with the shaft by means of a friction 45 clutch comprising a friction wheel 18 keyed to the shaft, friction blocks 19, a disc 20, and bolts 21 for adjusting the position of the disc. Obviously, by setting up on the bolts 21 the blocks carried by the friction wheel 50 will be caused to frictionally engage the worm wheel so that the worm wheel and shaft will rotate together. This construction provides a safety device, in that if some accidental disarrangement or obstruction occurs 55 tending to prevent the rotation of the table, the friction clutch will slip, thereby preventing the further damage which would follow if there was a positive connection between the worm wheel and the shaft 13. A motor 60 22, preferably of the variable speed type, drives a pinion 23 which meshes with a gear 24 fixed to a shaft 25, and this shaft carries a worm 26 meshing with the worm wheel 17.

It is thus seen that the mold-carrying table 65 is given a rotary step-by-step movement

through the medium of the Geneva stop construction, and that the driving mechanism for the Geneva wheel includes a safety device in the form of a friction clutch to prevent damage to the apparatus when some 70 unusual load is thrown on the driving mechanism because of an accidental obstruction to the moving parts.

The shaft 13 for driving the mold table functions also as the means for rotating the 75 cams controlling the operation of the various valves commonly employed in machines of this character. For this purpose a gear 27 is fixed to the shaft 13 and meshes with an intermediate gear 28 carried by a bracket 29 mounted on a pair of standards 30, 30; the standards also assisting in the support of a plate 31 carrying the various air valves. The intermediate gear 28 meshes with a gear 32 which is fixed to a shaft 33, and this shaft, 80 as shown in Figure 6, carries cams 34 for operating the air valves 35. The cams and the means for operating the valves may be of any well known construction, and as they 85 form no part of the present invention it is 90 believed to be unnecessary to illustrate in detail this part of the apparatus. However, the preferred construction is illustrated in a general way in Figure 6, and by reference to that figure it will be seen that a lever 36 is 95 operatively connected at one end with the air valve 35 and that the opposite end of the lever is forked and carries rollers 37 which are alternately engaged by the cams 34, 34. The forked construction of the lever is 100 clearly shown in Figure 1. Of course, there are a number of these valves not shown, and the connections from the valves to the various cylinders are also not shown, as the arrangement may be such as is desired and 105 involves no invention.

The rotary table 2 carries a series of molds, and these molds are carried step by step from the charging station, where the gob of glass is delivered to the blank mold, to the 110 station where the finished articles are delivered from the molds and automatically transferred to a conveyer. Each complete mold consists of a blank mold H, a neck mold I, a body or blow mold J, and a mold 115 bottom K.

The means for mounting the body mold, neck mold, and mold bottom on the table, the means for opening and closing the body and neck molds, and the means for sliding the mold bottom into and out of operative 120 position will now be described.

Numeral 38 (Figure 4) refers to a mold bottom guide plate which is bolted or otherwise fixed to the mold table, and acts as a 125 guide for the mold bottom K as it is moved inwardly and outwardly in a manner to be subsequently described. Mounted on the plate 38 is a U-shaped bracket 39, the upper and lower arms of which serve as mount- 130

ings for the hinge rod 40. The upper arm of the U-shaped bracket 39 extends inwardly, as indicated by numeral 41, and this projection is adapted to fit into a recess 5 formed in the bottom of the neck mold and top of the body mold, by which simple construction the neck and body molds are held in proper vertical alignment with the blank mold H. Both the neck mold and body 10 mold are formed as usual in two sections, and the sections are hingedly mounted on the hinge rod 40, as clearly shown in Figure 4.

In the operation of the machine the neck 15 mold and body mold are both open at some stations; both are closed at other stations; the neck mold is closed and the body mold open at another station; and at still another station the neck mold is open and the body 20 mold is closed. To automatically open and close the molds two superposed cams are employed, and for an understanding of the cam structure and the connections between the mold sections and the cams reference 25 is to be had particularly to Figures 2 and 4.

Two stationary cams 42, 42 are mounted on the column 1; and the cams are provided on their lower faces with cam tracks 43 and 44, numerals referring respectively to 30 the upper and lower cam tracks. Except for the contour of the cam tracks, the upper and lower cams and associated elements for operating the mold sections are identical in construction, and a description of one of 35 them will be sufficient. Cam slide plates 45 are mounted for rotary movement on the column 1, and these plates are caused to rotate together and with the mold table in a manner to be hereinafter described. Cam 40 slides 46 are mounted for reciprocatory movement on the slide plates, and these cam slides carry rollers 47 engaged in the cam tracks 43 and 44, by which arrangement the slides are moved inwardly and 45 outwardly in accordance with the contour of the cam tracks. A yoke 48 is provided for each neck mold and for each body mold, and these yokes are operatively connected with the neck and body molds respectively 50 by means of links 49 pivotally attached to the yokes and to lugs on the neck and body molds, as clearly indicated in Figure 2. Each yoke has an integral rod 50 slidably mounted in the cam slides 46, and the yoke 55 and rod are normally held in their forward position, with respect to the slide, by means of a coil spring 51 mounted on the rod within the slide. The operation will be obvious. As the slides move forward, due to the engagement of the rollers in the cam track, the rod and yoke will be carried forward with them and the link connections with the molds will cause the latter to be closed. 60 The resilient mounting of the yoke in the slides provides a safety device, for it is

apparent that if some unusual obstruction 65 prevents the closing of the molds no breakage of parts will occur, for the slide will merely move forward against the pressure of the spring, while the yoke and rod remain stationary.

The cam tracks 43 and 44 are of irregular contour; the contour being so designed that the neck and body mold sections will be opened, closed, or remain unchanged, in 70 accordance with the requirements of the machine, as the molds are moved from station to station. As hereinbefore stated, both molds are open at some stations, and both are closed at other stations, and consequently the upper and lower cam tracks coincide at such stations, as clearly shown 75 in Figure 2. On the other hand, the neck mold is closed and the body mold open at one station, and the neck mold open and 80 the body mold closed at another station; and, of course, at these stations the cam tracks are out of coincidence, which is also 85 clearly shown in Figure 2. The opening or closing of the molds as they travel from 90 station to station, and their open or closed position at each station, will be fully described hereinafter.

As previously stated herein, the upper and lower cam slide plates 45 are caused to 95 rotate together and with the mold table, and for a clear disclosure of the simple means by which this is accomplished reference is to be had to Figure 16. Rods 52 are mounted in the mold table 2, and these 100 rods are engaged in notches provided in the upper and lower cam slide plates, thus imparting to both plates the same rotary movement as that of the mold table. It will be understood, of course, that the rods 52 105 are so spaced as not to interfere with the inward and outward movement of the cam slides 46 and yokes 48.

For a disclosure of the means for moving the mold bottom K into and out of operative position, reference is to be had to Figures 1, 3 and 4. The mold bottom is mounted on a slide 53 adapted to reciprocate in the guide plate 38 secured to the mold table. The slide carries a roller 54 115 which is adapted to engage an irregular stationary cam track 55 during a portion of the travel of the mold table. An inspection of Figure 1 will show that the track 55 is so designed as to draw the slide 53 120 and mold bottom K outwardly to the full extent as the table travels from station F to station G. From station G to station B the contour of the cam track is concentric 125 with the center of the mold table, and hence the mold is retained in its withdrawn position until it reaches station B, at which point the track terminates. A cylinder 56 carrying a plunger 57 is arranged at the 130 terminal of the track 55. The cylinder is

preferably operated by fluid pressure, being automatically controlled by one of the valves 35 hereinbefore referred to. At the proper instant, and after the blank mold has been lowered to its inoperative position, the cylinder and plunger function to push the mold bottom into its operative position in alignment with the center of the mold. The mold bottom remains in this position until it again reaches station F, at which point the roller engages the track 55, and as the table moves to station G the mold is drawn outwardly to inoperative position.

15 The blank mold H and the means for operating same will now be described, reference being had particularly to Figures 3, 4, 6, 15 and 21. Before describing the details of construction it may be well to state generally the operation of the blank mold. The mold is mounted for vertical sliding movement, and as the mold approaches the charging station, i. e., station A, it is elevated by an inclined track into position to receive the glass gob; both the neck mold and body mold being open. Particular attention is called to the fact that the neck mold and body mold are open at the charging station, as this is one of the very material features of the invention, in that it makes it possible to drop a larger gob of glass than would be possible if the neck mold were closed. In the former practice the neck mold was usually closed during the charging operation, and, while such practice is satisfactory for wide mouthed ware, it is obviously not practicable for narrow necked ware, for it is impossible to feed a gob of sufficient size through the restricted neck mold. However, in accordance with the present invention, the neck mold is open during the charging operation, and hence the gob is not limited as to size, and the machine is thus adaptable to the manufacture of a wide field of articles, ranging from very narrow necked ware to large mouthed ware. After receiving the gob the mold is moved toward the next station, remaining in its elevated position, and during this movement the neck mold is closed. Just before reaching station B, and after the neck mold is closed, the blank mold is given a sharp rise, causing it to interlock with the neck mold. After the pressing plunger has descended to cause the initial displacement of the glass, the blank mold is lowered to its inoperative position, where it remains until it again approaches the charging station.

20 By reference to Figures 4 and 9 it will be seen that a valve 183 is mounted in the bottom of the blank mold, and this valve has a slight vertical movement limited by the pin 184. The purpose of this construction is, of course, to admit air into the bottom of the mold when it is lowered from the blank. The stem 58 also projects into the blank mold and is detachably connected thereto by a cotter pin 185. Referring now to Figure 15, it will be seen that the stem 70 58 of the blank mold H is mounted in a carrier 59; the latter being slidably mounted on a pair of parallel standards 60, 60 fixed to the mold table and of such length as to permit the blank mold to descend below the table. In Figure 15 the mold is shown in dotted lines in its lowered position, and in full lines in its elevated position. The carrier 59 is provided on one side with a roller 61 which is adapted to engage a 80 track 62 extending part way around the machine; the track being clearly shown in elevation in Figure 3, and a developed view of the track being illustrated in Figure 21. Assuming the mold to be in its lowermost position and carried by the standards 60; then when the table has rotated to a certain position the roller 61 will engage the track 62, and upon further rotation of the table the roller will ride up the inclined 85 portion of the track, thus elevating the blank mold until it reaches the horizontal portion of the track, indicated by numeral 63; and it is in this elevated position that the mold reaches the station A, where the 90 glass charge is delivered. Upon further travel of the table and mold, and just as the mold reaches station B, or the pressing station, the roller 61 engages the sharp rise 64 in the track 62, and this elevates the mold 10 still farther and causes the flange 65 at the top of the mold to engage in a recess 66 in the bottom of the neck mold, thereby interlocking the blank mold and neck mold, as clearly shown in Figure 4. The construction might be modified, as illustrated in Figure 9, wherein the flange 65 engages about a depending collar 67 formed on the bottom of the neck mold.

10 Just after the blank mold has been given the final elevation to interlock it with the neck mold, the roller 61 passes off of the track and onto a vertically movable carriage 68 (Figure 4). The carriage 68 is carried by the piston rod 69 of a cylinder 70, to which cylinder fluid pressure is automatically admitted and exhausted at the proper time by the operation of one of the valves 35. Another fluid pressure cylinder, indicated by numeral 71, is mounted on an anvil 72. The piston rod 73 of this cylinder operates a suitably mounted arm or block 74, and the cylinder is operated in timed relation by one of the valves 35 so that the arm or block 74 is pushed forward under the stem 58 of the blank mold just after the roller passes onto the carriage 68; and this arm or block relieves the carriage of the pressure exerted by the plunger as it descends at this station. The opposite end of the piston rod 73 ex-

110

115

120

125

130

135

tends through the rear end of the cylinder 71 and has nut locks 186 mounted thereon, whereby the limit of stroke of the piston is varied. This variation in the limit of 5 stroke is desirable to take care of wear on the arm or block 74. After the plunger has descended, pressure is admitted to the opposite end of cylinder 71, thereby withdrawing the block or arm 74 from beneath the 10 stem 58 and leaving the blank mold supported by the carriage 68 and free to be lowered. By the operation of cylinder 70 the carriage and mold are lowered to a position beneath the table, leaving the glass 15 blank supported by the neck mold.

It is to be noted that the body mold is open when the blank mold is in operative position with the neck mold, and thus the 20 present construction differs radically from the well known telescoping blank molds. This feature is of importance, for obviously in the present construction the size of the blank mold is not limited by the interior dimensions of the body mold, and thus the 25 present machine is adapted to make articles of a larger variety of sizes than is possible with a machine employing the telescoping blank molds. As previously stated herein, the neck mold is open at the charging station, so that the size of the glass gob is 30 not limited by the restricted opening in the neck mold, and this feature is of material importance, as will appear hereinafter.

It is believed that the construction and 35 operation of the various molds will be clearly understood from the foregoing description. The operation of the entire machine will now be described, and during the course of this 40 description the apparatus employed at each station will be described in detail.

The operations commence at station A, the charging station. The blank mold H has been elevated to charging position by the inclined track 62, and both the neck 45 mold and body mold are open. The molten glass flows in a stream from a flow spout, is sheared by any well known means, as, for instance, by the shearing mechanism illustrated in my pending application No. 403- 50 068, filed August 12, 1920, and the severed gob drops between the open molds into the blank mold H.

The arrangement of the parts at station A has not been illustrated in the drawings, 55 except as shown in Figure 8. The only operation performed at this station is the charging of the glass to the blank mold; this operation, however, presents a wide departure from the prior practice. In the prior 60 practice the neck mold has been closed at the charging station and this is not practical for narrow necked articles, for it would be impossible to deliver a glass gob of sufficient size through the restricted opening 65 in the neck mold. In the present apparatus

the neck mold is open during the charging operation, so that the glass gobs, whether large or small, drop freely into the blank mold; and hence the present apparatus is equally well adaptable to either wide or narrow necked articles. Figures 1 and 2 show the neck and body molds open and the blank mold arranged in operative position between them, and Figure 8 gives a detail view of the blank mold after it has been charged. 70 75

After the blank mold has been charged the mold carrier or table is rotated to station B, or the pressing station, by the Geneva wheel 10. As the table rotates from A to B the roller 47 traveling in the upper cam track causes the neck mold sections to be closed in the manner previously described. By an inspection of Figure 2 it will be seen that between stations A and B the upper cam track is of a contour designed to close 80 the neck mold at this point; and it will also be apparent that the contour of the lower cam track 44, shown in dotted lines, is such as to retain the body mold sections in open 85 position. After the neck mold has been 90 closed, further travel of the table causes the blank mold to be elevated into interlocking engagement with the neck mold, this further elevation of the blank mold being effected by the sharp rise 64 in the 95 elevating track 62. It is thus seen that when the pressing station is reached the neck mold is closed and is in engagement with the blank mold, and that the body 100 mold is open. Prior to the pressing operation the neck mold is locked by means of a locking clamp designated generally by the letter L. The locking clamp is employed at several of the stations, and it will be described in detail hereinafter. 105

The apparatus for performing the pressing operation will now be described, reference being had particularly to Figures 3, 4 and 9. The pressing apparatus is referred to generally by the letter M, and includes 110 the usual plunger 75 carried by the piston rod 76. The plunger is adapted to pass through a suitable aperture provided in a spring plate 77, and this spring plate is resiliently attached to the piston rod 76 by 115 two or more rods 78 fixed to the spring plate and slidably mounted in a collar 79 attached to the piston rod; coil springs 80 being mounted on the rods between the spring plate and collar. The spring plate carries 120 a neck ring 81 which is adapted to seat in the recess 82 in the neck mold (Figures 4 and 9). The piston rod is operated by a cylinder 83 which is controlled by one of the valves 35, as clearly shown in Figure 1. Referring to Figure 3, it will be seen that the cylinder is provided with an emergency valve 84 adapted to be operated by a hand lever 85. So that, while the operation of 125 the valve 35 may continue, the operator may 130

at will stop or start the operation of the plunger; this control being particularly for use when the machine is being started at the beginning of operations, to retain the 5 plunger in its elevated position while the glass and molds are being conditioned for pressing. And in case of an emergency the hand lever and valve may be operated to cause the plunger to assume an upwardly 10 sustained inoperative position.

The operation will be apparent from the foregoing description. Pressure being admitted to the top of cylinder 83 causes the piston rod to descend, carrying with it the 15 plunger, spring plate and neck ring. The neck ring 81 is first seated in the recess 82 provided in the neck mold I, and the plunger continues its downward movement and displaces a portion of the glass charge, forcing it up into the cavity of the neck and 20 handle portion of the neck mold. Pressure is then admitted to the bottom of the cylinder, thereby withdrawing the plunger and lifting the spring plate and neck ring free 25 of the neck mold.

At the same time the plunger is lifted the arm or block 74 is withdrawn by the operation of cylinder 71, leaving the blank mold supported by the carriage 68 and ready to 30 be lowered into inoperative position, and this is now accomplished by the operation of cylinder 70. After the blank mold has been lowered to inoperative position, leaving the pressed blank suspended by the neck 35 mold, the cylinder 56 is operated and its plunger pushes the slide 54 and with it the mold bottom K into alignment with the center of the mold body; and the clamp L is released from locking engagement with the 40 neck mold, leaving the mold free to be moved. Immediately thereafter the table is moved to station C, or the cooling station, by means of the Geneva wheel.

In connection with the plunger-operating 45 mechanism and the motor for driving the mold table, I employ a safety device by which the electrical-control mechanism is rendered inoperative whenever, for any reason, the fluid pressure supply to the plunger-operating cylinder or other cylinders is shut off, thus preventing the breakage of parts 50 or the disorganization of the machine. And this safety mechanism also renders it impossible for the operator to inadvertently 55 start the motor driving the mold table before having admitted pressure to the various cylinders to insure the proper operation of the machine. The safety mechanism is of general application to all glass machines 60 employing fluid pressure and electricity for the operation thereof, and, as the mechanism is in no way limited to use with the present machine, it is thought to be entirely unnecessary to illustrate the apparatus herein. However, a full disclosure of the safety 65

mechanism will be found in application Serial No. 660,057, filed by myself and David Stenhouse August 9, 1923.

During the movement of the table from station B to station C, or the cooling station, 70 the body or blow mold J is closed about the pressed blank. The closing of the body mold is accomplished by the engament of the lower roller 47 in the lower cam track 44, and an inspection of Figure 2 will show 75 that the contour of the lower cam track 44 is such as to come into coincidence at station C, so that both the neck and the body mold are closed at this point. The molds are maintained in closed position by the pressure exerted by the cam-operated closing means, and, as no pressure is exerted on the interior of the molds at the cooling station, it is not necessary to employ the locking clamps L at this station. 85

The apparatus for cooling the pressed blank indicated generally by letter N is clearly shown in Figure 5; and in the following description reference is to be had to that figure and to Figure 10. 90

Prior to the blowing operation it is desirable to cool the pressed blank at the thicker portion, and without unduly cooling the neck portion which is detrimental to the finished product. The practice before the 95 present invention was simply to blow air into the top of the blank after the plunger had been withdrawn; but obviously such a practice results in cooling the neck portion of the blank to the same extent that the 100 thicker portion of the blank is cooled. The purpose of the present cooling apparatus is, therefore, to cool the blank at the desired point only, and also to provide the apparatus with a selective feature, whereby the point 105 of cooling may be varied to suit various articles.

The cylinder for operating the cooling means is indicated by numeral 86, and it is provided with the usual pipes 87 and 88 at the top and bottom, respectively, for admitting pressure to the cylinder on opposite sides of the piston 89; the admission and exhaust of the fluid pressure being controlled by one of the valves 35. The piston carries 110 a hollow piston rod 90 and attached to the lower end of the piston rod is a hollow pipe 91 adapted to be projected into the interior of the pressed blank, and provided with apertures 92 at its lower end to permit the cooling air to escape into the interior of the blank at the desired point. Adjacent the upper end of the piston rod a port 93 is provided for the purpose of admitting the air or other fluid from the cylinder to the interior of the rod; and the volume of the fluid admitted to the rod is controlled by a regulator valve 94, which is vertically adjustable by a threaded portion 95 to vary the size of the inlet port. A sleeve 96 sur- 115 120 125 130

rounds the piston rod 90, and is screw threadedly mounted in the lower end of the cylinder 86; the sleeve being vertically adjustable and adapted to be held in adjusted position by means of a lock nut 97. The operation of the device may be briefly described as follows:

Referring to Figure 5, assume that the piston 89 has been moved to the top of the cylinder 86, thereby withdrawing the cooling pipe 91 from the interior of the blank. With the piston at the upper end of its travel it will be apparent that the port 93 will be clear of the cylinder and open to the atmosphere. The regulator valve 94 will be adjusted to regulate the size of the port and thereby control the volume of fluid admitted to the rod. Now when fluid pressure is admitted above the piston, the latter will be moved downward, but the fluid will not pass into the hollow piston rod until the piston and rod have moved a sufficient distance to bring the port 93 into the interior of the cylinder. When the piston and rod have moved sufficiently to permit communication between the interior of the cylinder and the interior of the rod the pipe 91 will have been projected into the interior of the pressed blank, and the air entering the rod through the port 93 will escape through the apertures 92 into the interior of the blank, thereby cooling the same. As clearly shown in Figures 5 and 10, the point at which the cooling air is projected against the blank is well below the neck portion, so that this thinner portion receives little, if any, of the cooling effect. For different articles it may be desirable to apply the air at different points, and it is obvious that the point of application of the air may be quickly and easily varied by the simple adjustment of the sleeve 96, thereby varying the limit of the down stroke of the piston and parts carried thereby. It is thus seen that the apparatus disclosed herein is selective as to the point at which the blank will be cooled; that the volume of the cooling air may be easily varied by the adjustment of valve 94; and it will be apparent that the use of the hollow piston and port construction obviates the necessity for the use of a flexible hose and valves such as have been commonly employed heretofore.

The duration of the cooling operation is variable, of course, and is controlled by the timing of the valve 35 associated with the cylinder 86. At the termination of the cooling operation the piston rod 90 and pipe 91 are lifted clear of the blank and mold; and the mold is ready to be moved to station D by the operation of the Geneva wheel.

In traveling from station C to station D, or the first blowing station, both the neck mold and body mold are retained closed, and an inspection of Figure 2 will show that the

upper and lower cam tracks are in coincidence from station C to station D. As the blowing operation is performed at station D, it is necessary to have both molds locked in closed position, and by reference to Figure 6 it will be seen that two of the clamps L have been provided for that purpose. These clamps are, of course, automatically operated by the valves 35 to lock the molds as soon as they reach station D.

The apparatus for performing the first blowing operation is indicated generally by the letter O, and in the following description reference is to be had particularly to Figures 6, 11 and 17.

The blower head is indicated by numeral 98, and it is adapted to fit against the top of the neck mold during the blowing operation and convey air under pressure to the interior of the neck and body molds to distend the blank to the shape of the interior of the blow mold in the well known manner. The blower head is raised and lowered by a hollow piston rod 99 which is loosely connected to the blower head to provide for irregularities. The particular loose coupling illustrated herein includes a short nozzle 100 screw threadedly mounted on the piston rod and having a ball flange 101 on its lower end; the flange being mounted in a recess 102 in the blower head and held in place by a cap 103 detachably connected to the blower head. The hollow piston rod 99 is attached to the piston 104 in the operating cylinder 105, and the piston rod extends on through the top of the cylinder. The upper portion of the hollow piston rod is provided with a port 106 for the admission of air to the interior of the rod when the rod has descended far enough to bring the port within the interior of the cylinder. Air or other fluid pressure for operating the piston is supplied to the top and bottom of the cylinder by the pipes 107 and 108 controlled by one of the valves 35, and the volume of air passing from the cylinder to the interior of the rod is controlled by a regulator valve 109 screw threadedly mounted in the top of the rod.

The pressure in the blow mold is controlled by a relief valve preferably of the ball type, as indicated by numeral 110. The pressure in the blow mold is communicated to the ball valve through the passages clearly shown in Figure 17, and if this pressure becomes too great it will lift the ball from its seat against the pressure of the coil spring 111, and permit the fluid to escape to the atmosphere through the passage 112, thereby reducing the pressure to the desired extent in the article being blown. The tension of the spring against the ball is adjusted to suit conditions by the screw 113.

In the operation of the blower apparatus air or other fluid pressure is admitted above the piston to force it downwardly, thereby

seating the blower head 98 on the neck mold I, and when the piston rod has moved downwardly to a sufficient extent the port 106 is brought within the interior of the cylinder 105, thereby opening communication between the interior of the cylinder and the interior of the rod, and thus permitting the air or other fluid under pressure to flow through the rod, nozzle and blower head to the interior of the article to be blown. The volume of air supplied to the mold is adjusted by the regulator valve 109, and excessive pressure in the mold is relieved by the valve 110. Figure 11 shows the article after 15 it has been blown.

The structure above described provides an extremely simple apparatus for effecting the blowing operation; and it will be apparent that the loose coupling between the piston rod and blower head will allow for any irregularities and will result in a tight fit between the blower head and neck mold; and it will also be apparent that the hollow piston and port construction greatly simplifies the apparatus, eliminates the use of flexible hose and valves commonly employed heretofore.

When the blowing operation is completed pressure is admitted to the opposite side of the piston, thereby lifting the blower head and cutting off communication between the interior of the cylinder and the interior of the rod. The locking clamps are now opened and the mold table is ready to be moved to station E.

As the mold table is rotated from station D to station E, or the second blowing station, the neck mold is opened while the body mold is retained closed. An inspection of 40 Figure 2 will show that the contour of the upper cam track between stations D and E is such as to open the neck mold.

In the following description of the second blower reference is to be had to Figures 7, 45 12 and 18.

The second blowing apparatus is indicated generally by the letter P, and its purpose is to supply air pressure sufficient to keep the blown article distended to contact with the mold. The second blower head is indicated by numeral 114, and, as shown in the drawings, this blower head is bell-shaped and is adapted to fit down on the body mold and over the neck of the jug or other article, so that the neck of the article is inclosed within the bell-shaped blower head. Figures 7 and 12 show the second blower head in operative position, and its relation to the neck of the article. A recess 115 is provided in the top of the blower head for the purpose of loosely coupling it with a hollow piston rod in exactly the same manner as described in connection with the first blower head and as illustrated in Figure 17. Further, the cylinder for operating the second

blower head, the port for admitting the air from the cylinder to the interior of the piston rod, and the regulator valve for controlling the volume of air admitted are all identical in construction with the apparatus disclosed in connection with the first blower head, and consequently it has not been deemed necessary to illustrate the operating mechanism in connection with the second blower head. However, Figure 7 shows a portion of a hollow piston rod 116 having a ball flange 117 seated in the recess 115, and loosely held in place by the plate 118.

The blower head 114 is also provided with a relief valve, as indicated by numeral 187, and as this valve is of the same construction as the relief valve 110 of the first blower head it need not be described in detail.

As previously stated, this second blowing operation is for the purpose of setting the glass permanently in its molded form. After the completion of this second blowing operation the locking clamp 4 is opened and the article should be sufficiently set to permit the opening of the body mold, and, in accordance with the present disclosure, this is done on movement to the next station. It will be understood, however, that where the article is of such a character as to require more time to set the cam track may be changed to open the mold at a later station.

The formation of the article is now complete and the two remaining stations relate to the opening of the mold and the delivery of the finished article; but before describing these two stations the specific construction of the locking clamps L will be described.

The locking clamps L are employed at stations B, D and E; two superposed clamps being employed at station D, as both the neck and body mold are locked at this station. In the following detailed description reference is to be had particularly to Figure 19. Numeral 119 indicates an ordinary cylinder provided with a piston 120, and operated in the usual manner by air or other fluid pressure; the operation of the cylinder being controlled by one of the valves 35. Guide rods 121, 121 are attached to the cylinder mounting and extend forwardly in spaced parallel relation. The guide rods 121, 121 are connected at their forward ends; and where two complete mold clamps are employed, as at station D, I prefer to employ a plate 122 for this purpose, whereby all four of the guide rods are maintained in proper spaced and parallel relation. Obviously, if only a single unit were employed, then an ordinary crossbar would be substituted for the plate 122.

A crosshead 123 is slidably mounted on the guide rods 121, 121, and this crosshead is connected to the piston rod 124 carried by the piston 120. The crosshead is connected

to the piston rod by a pin and slot connection, as indicated by numerals 125 and 126, respectively, whereby relative movement between the crosshead and piston rod is permitted.

Clamping jaws 127, 127 are pivotally mounted on the crosshead 123, and these pivotally mounted jaws are operatively connected to a head-piece 128 by means of pivotally mounted links 129; the head-piece 128 being mounted on the piston rod in fixed relation thereto. The links 127 operate through slots 130 provided in the guide rods for that purpose. A coil spring 131 is mounted on the piston rod 124 between the crosshead 123 and head-piece 128, and normally holds the crosshead in its forward position on the piston rod, for a purpose to be described hereinafter.

The operation of the apparatus will now be described; it being assumed that the clamp is in its withdrawn or inoperative position.

The admission and exhaust of air to the operating cylinder is, of course, in timed relation with the operation of the glass machine, and when a mold reaches a station where it is to be clamped air is automatically admitted to the rear of piston 120, thereby forcing the piston and its rod 124 forwardly. As the rod moves forwardly it carries with it the head-piece 128; and because of the pressure of the coil spring 131 the crosshead 123 is maintained in its foremost position on the piston rod; i. e., the pin 125 remains in the forward end of the slot 126. It is thus seen that there is no relative movement between the crosshead 123 and the head-piece 128, and thus all the parts move forward in exactly the same relative position as they occupy when the device is in inoperative position. This forward movement, without relative change of position of the moving parts, continues until the crosshead contacts with the plate or crossbar 122, and at this point the parts are in the position shown in dotted lines in Figure 19; the clamping jaws still remaining in open position, but having been carried forward until they are in alignment with the ordinary clamping lugs provided on the glass molds.

The crosshead remains in its position abutting the member 122, but the pin and slot connection with the piston rod permits the latter to continue its forward movement, carrying with it, of course, the head-piece 128. And obviously this further forward movement of the head-piece causes the clamping jaws, through the connecting links 129, to swing inwardly and clamp the mold in closed position.

From the foregoing description it will be apparent that it is impossible for the clamping apparatus to exert any pressure what-

ever on the mold tending to displace it; for the clamping jaws are moved to their extreme forward position while still open, and thus it is impossible to subject the mold to any pressure other than the pinching or closing pressure.

At the proper moment the air is released from the rear of the cylinder and pressure is admitted to the front thereof, and the movement of the parts is exactly the reverse of that described above. The spring 131 retains the crosshead in its forward position, while the head-piece moves to the dotted line position, thereby moving the clamping jaws to the open position, also shown in dotted lines. At this point the pin 125 strikes the forward end of the slot 126, and further rearward movement of the piston rod carries the parts, in open position, to the inoperative position of the apparatus.

No claim is made herein to the clamping mechanism per se, as it forms the subject-matter of a separate application, Serial No. 663,221, filed September 17, 1923.

Returning now to the description of the operation of the jug machine, the formation of the article has been completed at station E, or the second blowing station, the blower head has been lifted and the locking clamp has been released from the body mold. The table is now ready to be rotated to station F.

During the rotation of the table from station E to station F the body mold is open, leaving the finished article resting on the mold bottom. An inspection of Figure 2 will show that the upper and lower cam tracks come into coincidence at station F, with both molds open. Figure 13 shows a detail view of the finished article resting on the mold bottom with both the neck mold and body mold open. The table is now ready to be rotated to station G.

During the movement of the table from station F to station G the slide 53 is withdrawn, carrying with it the mold bottom K on which is resting the finished article. Figure 14 is a detail view showing both molds open, the mold bottom withdrawn, and the finished article resting on the mold bottom. The mechanism for withdrawing the mold bottom is illustrated in Figures 1 and 3. By reference to these Figures it will be seen that the roller 54 carried by the slide 53 engages the track 55 at station F. The track 55 extends outwardly from station F to station G, as clearly shown in Figure 1, so that when the table has reached station G the slide and mold bottom have been withdrawn to the full extent, and the finished article is ready to be lifted from the mold bottom and transferred to any suitable point, such as the conveyer Q for carrying the finished ware to the lehr. The automatic transfer device is indicated generally by the letter R,

and in the following description thereof reference is to be had particularly to Figures 1, 3 and 20.

A cylinder 132 is provided with a piston 133 and piston rod 134, which are caused to reciprocate in the usual manner by air or other fluid pressure admitted to opposite ends of the cylinder through appropriate ports 135, 135. Tracks 136 extend outwardly from the cylinder, and are maintained in parallel relation by a spacer 137. A carriage 138, mounted on rollers 139, is adapted to reciprocate on this track; the carriage being reciprocated by means of the piston rod 134, which is directly connected to a cylinder 140 mounted on the carriage.

The cylinder 140 is provided with ports 141 and 142 for controlling the reciprocation of the piston 143 and piston rod 144; and 20 associated with the ports are pipes 145 and 146, which are telescopically mounted in the cored chambers 147 and 148, to which air or other fluid pressure is alternately admitted through the ports 149 and 150, respectively. 25 Mounted on the lower end of the piston rod 144 is a cross bar 151 having a pin and slot connection, indicated by numerals 152 and 153, with grippers 154, 154 pivotally attached at their upper ends to a head member 155 slidably mounted on a sleeve 156 which is threaded to the lower cylinder head 157 of cylinder 140. The threaded portion of the sleeve 156 is preferably split, and the clamp 158 is provided for rigidly holding 30 the sleeve in adjusted position. A collar 159, preferably adjustable, is mounted on the lower portion of the sleeve beneath the head member 155; the latter being held against the collar by the pressure of the coil spring 160. 35 40 also mounted on the sleeve and having its compression controlled by an adjustable cap 161.

The operation of the transfer device will now be described; it being assumed that the carriage has been retracted, and that the piston 143 is at the end of its down stroke.

Fluid pressure will be admitted to the chamber 148 through the port 150, and then passes through pipe 146 and port 142 to the 50 lower portion of cylinder 140. The piston 143 and rod 144 are thus lifted, and, due to the pin and slot connection between the crossbar 151 and grippers 154, the latter are drawn inwardly to grip the article; the 55 position of the parts being as shown in Figure 20. The pins 152 are now at the upper limit of their travel in the slots 153, and further inward movement of the grippers is prevented; but the piston 143 has only partly 60 finished its upward stroke, and as the piston and rod continue their upward movement the crossbar will lift the grippers and head member 155 bodily against the pressure of the spring 160.

65 Pressure will now be automatically ad-

mitted to the cylinder 132, causing the entire mechanism to travel outwardly on the tracks 136. At the end of this outward stroke of the piston 133 the carriage and entire gripping mechanism will be directly over the conveyer Q, upon which the article is to be deposited.

Air is now admitted to the chamber 147 and passes through the pipe 145 and port 141 to the upper end of cylinder 140. The piston 143 and rod 144 move downwardly and the spring 160 forces the head member down, so that the grippers are retained in their closed position. This bodily movement continues until the head member contacts with the collar 159, at which point the article is deposited on the conveyer. The piston rod continues its downward movement, and, through the engagement of the pins 152 in the slots 153, the grippers are moved to open position, so that the article is free to be carried along by the conveyer to its destination.

The operation is now repeated, the gripping mechanism being lifted, the carriage retracted, and the mechanism lowered to grip the next article, thereby completing the cycle of operations.

For ware of different height it will be necessary to vary the lowermost position of the grippers, and obviously this may be accomplished by adjusting the position of the sleeve 156 on the cylinder head 157.

No claim is made herein to the above described automatic transfer mechanism per se, as it forms the subject-matter of a separate application, Serial No. 663,222, filed September 17, 1923.

It is believed that the operation of the entire machine and the construction of all of its parts will be clearly understood from the foregoing description, and all that will be added here is a brief outline of the various operations.

As the mold table approaches station A the blank mold is elevated to its charging position, and the mold is charged in any well known manner; the neck mold and the body mold being open at this station, so that a charge of glass may be freely delivered to the blank mold, whether narrow or wide necked articles are being manufactured. During the rotation of the table from station A to station B the neck mold is closed and the blank mold is elevated further to interlock with the neck mold. The plunger then descends and forces the glass into the neck and handle portion of the neck mold. After this pressing operation the blank mold is lowered to its inoperative position, leaving the pressed blank suspended by the neck mold; and the mold bottom is pushed into alignment with the body mold. The table is now rotated to station C and during the movement from station B

to station C the body mold is closed, so that both molds are in closed position at station C. At this station the thicker portion of the pressed blank is cooled without 5 cooling the relatively thin neck portion, and the point at which the cooling fluid is applied is selective, as fully described hereinbefore. After the cooling operation the table is rotated to station D, both molds 10 being retained in closed position during this movement. At station D the first blower head is lowered to abut against the neck mold and pressure is admitted to the interior of the blank to distend it to the 15 form of the interior of the body mold. Upon completion of the first blowing operation the blower head is lifted and the table is rotated to station E. During the movement 20 of the table from station D to station E the neck mold is opened and the second blower head is lowered to abut against the body mold; the neck of the article being inclosed in the interior of the bell-shaped 25 blower head. The purpose of this second blowing operation is to set the glass permanently in its molded form. The actual manufacture of the article is completed at this station, and the remaining two stations relate to the removal of the article; 30 the body mold being opened upon movement of the table to station F and the mold bottom supporting the finished article being withdrawn by movement of the table to station G, where the article is picked up and 35 transferred to a conveyer by the automatic transfer mechanism R.

Obviously, the mechanism and the mode of operation are subject to various modifications without departing from the spirit of 40 the invention, and it is intended that all such modifications should come within the scope of the appended claims.

Having fully described the invention, what I claim as new is:

- 45 1. In a glass forming machine, means for pressing a glass blank, and means for selectively cooling the interior of the pressed blank, said means being adjustable to vary the point of application thereof.
- 50 2. In a glass forming machine, means for pressing a glass blank, and means for cooling substantially the thicker portion only of the pressed blank, said means being introduced into the interior of the blank.
- 55 3. In a glass forming machine, means for pressing a glass blank, and means for injecting a cooling medium into the interior of the blank, said cooling medium having a free exit to the atmosphere.
- 60 4. In a glass forming machine, means for pressing a glass blank, and means for injecting a cooling medium for cooling selected portions of the blank, said cooling medium having a free exit to the atmosphere.
- 65 5. In a glass forming machine, means for

pressing a glass blank, and means for introducing cooling air into the interior of the pressed blank below the neck portion, said cooling air having a free exit to the atmosphere.

70

6. In a glass forming machine, means for pressing a glass blank, and means for introducing cooling air into the pressed blank below the neck portion, said means being vertically adjustable.

75

7. In a glass forming machine, means for pressing a glass blank, means for introducing cooling fluid into the interior of the pressed blank, and means for varying the point of application of the cooling fluid.

80

8. In a glass forming machine, means for pressing a glass blank, means for cooling the pressed blank, said means including an operating cylinder, the operative fluid of said cylinder being utilized for the cooling operation, and said fluid having free exit to the atmosphere from the pressed blank.

85

9. In the manufacture of articles from plastic material, means for cooling the plastic material, the fluid for operating said means being utilized as the cooling agent, and said fluid having free exit to the atmosphere from the pressed blank.

90

10. In the manufacture of articles from plastic material, means for cooling the plastic material, the fluid for operating said means being utilized as the cooling agent, and means for varying the point of application of the cooling agent.

95

11. In the manufacture of articles from plastic material, means for cooling the plastic material, the air for operating said means being utilized as the cooling agent, and means for varying the point of application of the cooling agent.

100

12. In the manufacture of articles from plastic material, means for cooling the plastic material at selected points, the air for operating said means being utilized as the cooling agent, and means for controlling the volume of cooling air.

105

13. In the manufacture of articles from plastic material, a cylinder, a hollow piston rod operated by the cylinder and adapted to have communication with the interior thereof, whereby the cylinder operating fluid may flow through the hollow rod to be utilized for various purposes in the manufacture of the articles, and means for varying the lower limit of the hollow piston rod.

115

14. In the manufacture of articles from plastic material a cylinder, a hollow piston rod adapted to be projected into the interior of the partly formed article and to convey cooling fluid from the interior of the cylinder to the interior of the partly formed article, said fluid having free exit to the atmosphere from the partly formed articles.

125

15. In the manufacture of articles from plastic material, a cylinder, a hollow piston

130

- rod adapted to be projected into the interior of the partly formed article and to convey cooling fluid from the interior of the cylinder to the interior of the partly formed article, and means for varying the point of application of the cooling fluid, said cooling fluid having free exit to the atmosphere from the partly formed article.
16. In the manufacture of articles from plastic material, a hollow piston rod for applying air to the partly formed article, said rod having a port adapted to communicate with the interior of the operating cylinder, communication between the rod and cylinder through said port depending on the position of the rod.
17. In the manufacture of articles from plastic material, a hollow piston rod for supplying air to the partly formed article, said hollow rod having a port, said port adapted to be in communication with the interior of the cylinder in one position of the rod, and out of communication with the interior of the cylinder in another position of the rod.
18. In the manufacture of articles from plastic material, a hollow piston rod for supplying air to the partly formed article, said rod having a port adapted to communicate with the interior of the operating cylinder, communication between the rod and cylinder through said port depending on the position of the rod, and means for controlling the volume of air admitted to the interior of the hollow piston rod.
19. In the manufacture of articles from plastic material, a hollow piston rod for supplying air to the partly formed article, said rod having a port adapted to communicate with the interior of the operating cylinder, communication between the rod and cylinder through said port depending on the position of the rod, and means for selectively controlling the point of application of the fluid conveyed through said rod.
20. In the manufacture of articles from plastic material, a hollow piston rod for supplying air to the partly formed article, said rod having a port adapted to communicate with the interior of the operating cylinder, communication between the rod and cylinder through said port depending on the position of the rod, means for controlling the volume of air admitted to the interior of the rod, and means for selectively controlling the point of application of the fluid conveyed through said rod.
21. In a glass forming machine, a hollow piston rod for supplying air to the molds for various purposes, a cylinder for moving said rod into and out of operative position with respect to the molds, said rod being in communication with the interior of cylinder when in operative position, and out of communication with the interior of the cylinder when in inoperative position.
22. In a glass forming machine, a blower head, a hollow piston rod connected to the blower head and adapted to move the latter into and out of operative position with respect to glass molds, said hollow piston rod being in communication with the interior of its operating cylinder only when the blower head is in operative position.
23. In a glass forming machine, a blower head, a hollow piston rod connected to the blower head and adapted to move the latter into and out of operative position with respect to glass molds, said hollow piston rod being in communication with the interior of its operating cylinder when the blower head is in operative position, and out of communication with the interior of the cylinder when the blower head is in inoperative position.
24. In a glass forming machine, a blower head, a hollow rod connected to said blower head and adapted to move it to operative and inoperative position with respect to glass molds, said rod being in communication with a source of fluid under pressure when the blower head is in operative position, and out of communication with said source when the blower head is in inoperative position.
25. In a glass forming machine, a blower head, means including a cylinder and a hollow piston rod for moving the blower head into and out of operative position with respect to glass molds, said piston rod being in or out of communication with a source of fluid under pressure in the cylinder, depending upon the position of the blower head.
26. In a glass forming machine, a rotary table, a series of sectional neck and body molds carried thereby, a blank mold also carried by the table, the neck mold being open when the blank mold is being charged, and means operated synchronously with the rotation of the table for moving the blank mold into interlocking relation with the neck mold after the latter is closed.
27. In a glass forming machine, a rotary table, a series of sectional neck and body molds carried thereby, a blank mold also carried by the table, the cross sectional area of the blank mold being greater than the area of the opening in the neck mold, and means operated synchronously with the rotation of the table for moving the blank mold into interlocking relation with the neck mold after the latter is closed.
28. In a glass forming machine, a rotary table, means carried by the table for forming large narrow necked ware, said means including neck molds, body molds and blank molds, means causing the neck mold to be

open at the charging station, and means operated synchronously with the rotation of the table for moving the blank mold into interlocking relation with the neck mold after the latter is closed.

29. In a glass forming machine, a rotary table, blank molds carried by the table, an unobstructed passage from the charging apparatus to the blank molds during the 10 charging operation, whereby the glass gob is not limited as to size, neck molds carried by the table, means for closing the neck molds after the charging operation, and means operated synchronously with the 15 rotation of the table for moving the blank mold into interlocking relation with the neck mold after the latter is closed.

30. In a glass forming machine, means for forming either wide or narrow necked 20 ware, said means including blank molds, neck molds, said neck molds being open to provide a free passage to the blank molds during the charging operation, means for closing the neck molds after the charging 25 operation, and means operated synchronously with the rotation of the table for moving the blank mold into interlocking relation with the neck mold after the latter is closed.

31. In a glass forming machine, a rotary 30 table, a series of sectional neck and body molds carried thereby, a blank mold, also carried by the table, means for moving the blank mold into charging position at the charging station, both the neck mold and body mold being open at the charging 35 station, and means operated synchronously with the rotation of the table for moving the blank mold into interlocking relation with the neck mold after the latter is closed.

40. 32. In a glass forming machine, a rotary table, a series of sectional neck and body molds carried thereby, the neck mold being open at the charging station, means for closing the neck mold, a blank mold also carried 45 by the table, means for elevating the blank mold into interlocking relation with the neck mold, the body mold being open.

33. In a glass forming machine, a rotary 50 table, a series of sectional neck and body molds carried thereby, the neck mold being open at the charging station, a blank mold also carried by the table, means for elevating the blank mold to charging position and means for further elevating the blank mold 55 into interlocking relation with the neck mold at the pressing station.

34. In a glass forming machine, a rotary 60 table, a series of sectional neck and body molds carried thereby, the neck mold being open at the charging station, a blank mold also carried by the table, an inclined track for elevating the blank mold to charging position, said track having a sharp rise for further elevating the blank mold into inter-

locking relation with the neck mold at the pressing station.

35. In a glass forming machine, a rotary table, a series of sectional neck and body molds carried thereby, a blank mold also carried by the table, a track for elevating 70 the blank mold to its pressing position, a carriage onto which the blank mold passes after leaving the elevating track, and means for lowering the carriage when the pressing operation is completed. 75

36. In a glass forming machine, a rotary table, a series of sectional neck and body molds carried thereby, said neck molds being open at the charging station, a blank mold also carried by the rotary table, a track for elevating the blank mold to its pressing position, a carriage onto which the blank mold passes after leaving the elevating track, a supporting arm adapted to support 80 the blank mold during the pressing operation, means for withdrawing said arm, and means for lowering the carriage when the pressing operation is completed. 85

37. In a glass forming machine, a rotary table, a series of sectional neck and body molds carried thereby, said neck molds being open at the charging station, a blank mold also carried by the rotary table, means for elevating the blank mold to its pressing position, a supporting arm adapted to support 90 the blank mold during the pressing operation, and means for withdrawing said arm when the pressing operation is completed.

38. In a glass forming machine, a rotary 100 table, a series of sectional body molds carried thereby, a mold bottom slidably mounted on the table, a reciprocable plunger for moving the mold bottom into alignment with the body mold, and a cam track for withdrawing the mold bottom toward the periphery of the table. 105

39. In a glass forming machine, a rotary table, a plurality of sectional neck and body molds carried thereby, the neck molds being 110 separate from the body molds, a blank mold, means for elevating the blank mold into engagement with the closed neck mold at the pressing station, means for lowering the blank mold after the pressing operation is completed, reciprocable means for moving the mold bottom into alignment with the body mold, means for closing the body mold, and a cam track for withdrawing the mold bottom toward the periphery of the table 115 after the molds have been opened. 120

40. In a glass forming machine, a rotary table, a series of sectional body and neck molds carried by the table, means for pressing the glass blank at one station, means for cooling variable portions of the pressed blank at another station, and means for blowing the blank at another station. 125

41. In a glass forming machine, a single rotary table, a series of sectional body and neck molds carried by the table, means for pressing the glass blank at one station, ⁵ means for cooling the pressed blank at another station, means for blowing the blank at another station, and means for giving a permanent set to the blown article by introducing fluid under pressure into the interior thereof at another station.

42. In a glass forming machine, a rotary table, a series of sectional body and neck molds carried by the table, a blower head, means for applying the blower head to the ¹⁵ neck mold at one station, a second blower head, and means for applying the second blower head to the body mold at another station.

43. In a glass forming machine, a rotary table, a neck mold and body mold carried

thereby, said neck and body molds having a recess formed in the bottom and top, respectively, and a fixed lug adapted to fit into the recesses, whereby the molds are maintained in proper alignment.

25

44. In a glass forming machine, a rotary table, a bracket mounted thereon, a neck mold and a body mold hingedly mounted on the bracket, said neck and body molds having a recess formed in the bottom and ³⁰ top, respectively, and an extension on said bracket adapted to project into the recesses.

45. In a glass forming machine, a rotary table, a series of neck molds, body molds and blank molds carried by the table, a stem for ³⁵ raising and lowering the blank molds, and a removable pin connection between the stems and blank molds.

THOMAS STENHOUSE.
